PROTECTIVE GUIDE DEVICE FOR WELL INSTRUMENTS

Charles P. Collins, Denver, Colo., and Charles A. Brokaw, Dallas, Tex., assignors to Eastman Oil Well Survey Company, Denver, Colo., a corporation of Delaware

Application August 2, 1946, Serial No. 687,838

2 Claims. (Cl. 73—151)

1
This invention relates to new and useful improvements in protective guide devices for well instruments.

One object of the invention is to provide an improved device which is particularly adapted for use with the outer barrel or casing of a well instrument and which functions to guide and center said barrel or casing within the well pipe or bore as the same is lowered or raised therethrough, said device also functioning to protect the casing and instrument against undue shock or jar during the lowering and raising operations.

An important object of the invention is to provide an improved guide and protective assembly which includes a flexible guide and centering element having longitudinally extending guide ribs or wings, said wings projecting outwardly from the body of the element and being disposed so as to be urged or folded inwardly toward the body when striking a projection or restriction in the well bore or pipe during lowering or raising of the assembly, whereby said element functions to efficiently center and guide the assembly and also to absorb any undue shocks or jars which may be encountered without interfering in any manner with the movement of the assembly through the well bore or pipe.

A particular object of the invention is to provide an improved guide and protective assembly adapted to be connected to the outer casing of a well instrument, said assembly having a flexible guide and centering element and also having means for connecting the assembly with a lowering line, whereby if desired, such line may be connected thereto to lower and raise the assembly and well instrument by means thereof; the connecting means being so disposed that when the lowering line is omitted and the assembly is "go-deviled" or dropped, said means is enclosed and protected and will not interfere with such lowering.

Still another object of the invention is to provide an improved flexible guide and protective element which includes an elongate cylindrical sleeve having longitudinally extending wings or ribs projecting outwardly therefrom, with said ribs being disposed at an angle in a vertical plane from a radial line extending from the center of the body, whereby when said ribs engage a projection or restriction, the wings or ribs are urged or folded inwardly toward the body and against their inherent resiliency, whereby the element may readily pass through a pipe or opening of considerably smaller diameter than the diameter

2
of the outer edges of the wings in their normal extended position.

The construction designed to carry out the invention will be hereinafter described together with other features of the invention.

The invention will be more readily understood from a reading of the following specification and by reference to the accompanying drawing, wherein an example of the invention is shown, and wherein:

Figure 1 is a view partly in section and partly in elevation showing the improved protective guide device connected with a well instrument barrel and illustrating the same in position within a drill collar.

Figure 2 is an enlarged, transverse, longitudinal section of the device.

Figure 3 is an enlarged horizontal cross-sectional view taken on the line 3—3 of Figure 1, and

Figure 4 is an enlarged, horizontal, cross-sectional view illustrating the flexible guide element in position within a drill pipe.

In the drawings, the numeral 10 designates a cylindrical metallic body having a downwardly extending cylindrical mandrel 11 which has a diameter less than the diameter of the body, whereby an annular shoulder 12 is formed at the intersection of the body and mandrel. The mandrel and body form a main support for the assembly and it is preferable, although not essential, that these parts be made integral with each other. The upper end of the body is formed with an upstanding externally screw-threaded pin 13 which is also preferably made integral therewith. The lower tubular end 14 of a retrieving element or head 15 is threaded onto the pin 13 and when so connected, as shown in Figure 2, the upper end of said pin is disposed within the bore 16 of said element. The element 15 has a fishing neck 17 formed with the usual undercut shoulder 18 at its upper portion, whereby a suitable retrieving tool (not shown) may be engaged therewith so as to retrieve the assembly and lift it upwardly from within a well bore, as will be explained.

In order to permit a lowering line or cable 19 to be connected with the assembly so as to lower and raise the same by means of said line, the retrieving element 15 has a reduced axial passage 20 which extends entirely therethrough and which communicates with the bore 16 at the lower end thereof. The line 19 is threaded through the bore 20 and is adapted to be secured to an upstanding ear or lug 21 which is formed integral

3

with the top of the threaded pin 13 of the body 10. Obviously, when the line 19 is connected to the ear 21, said line may be employed to lower the assembly within a drill pipe or and raise the assembly within a drill pipe or well bore. If the line 19 is not employed, the assembly may be dropped so as to fall by gravity and then may be retrieved by engaging a suitable retrieving tool (not shown) with the undercut shoulder 18 to lift the assembly back to the surface.

A flexible guide and centering member 22 is mounted on the cylindrical mandrel 11 and as is clearly shown in Figures 2 to 4, this member 22 comprises a sleeve or body portion 23 having a plurality of outwardly extending ribs or wings 24 which are made integral therewith. The member 22 may be constructed of neoprene, rubber or other flexible material. Any desired number of wings or ribs 24 may be disposed at equidistant points around the sleeve portion 23 and each rib has the upper portion of its longitudinal edge inclined inwardly at 25, while the lower portion of said longitudinal edge is inclined inwardly as indicated at 26. The inclination or beveling of the upper and lower portion of the longitudinal edges of the wings or ribs 24 will facilitate movement of the member through a drill pipe and past the various irregularities or couplings which may be encountered in said pipe.

The disposition of the ribs or wings 24 with respect to the center of the sleeve portion 23 and the mandrel 11 is an important feature of the present invention. Obviously, since the member 22 is constructed of rubber or flexible material the ribs or wings have an inherent elasticity or resiliency. This inherent resiliency normally holds the wings or ribs in the position shown in Figure 4 in which position the longitudinal axis of each rib is disposed at an angle with respect to a radial line extending from the center of the sleeve portion 23 and mandrel 11. Each wing or rib 24 is disposed more toward a tangential position with respect to the sleeve portion 23 than toward a true radial position. This locates the wings 24 in an angular position with respect to a radial plane within the drill pipe with the result that any pressure imposed upon the wings will tend to move the wings inwardly toward a folded position around the tubular portion 23 of the member, as indicated in Figure 3. This arrangement permits the flexible member 22 to readily pass through diameters which are considerably smaller than the normal outside diameter of the outer edges of the wings or ribs when in a normal position.

The flexible member 22 is retained in position on the mandrel 11 by a cylindrical adapter 27 which is threaded onto the lower end of the mandrel and which has its upper end engaging the lower end of the member 22. It will be evident that the flexible member 22 is confined between the adapter and the external shoulder 12 formed at the base of the body 10. When said member becomes worn and requires replacement it is only necessary to remove the adapter 27 to allow removal of the member 22 and replacement thereof by a new member.

The adapter 27 is formed with a downwardly extending connecting pin 28 which is adapted to thread into the upper end of an instrument barrel A. A well survey instrument B is housed within the barrel A and may be suitably protected against shock therein by coil springs C at each end of said instrument. A bull plug D closes the lower end of the barrel A. It is noted

that the barrel A may be of any desired construction, as may be the well instrument mounted therein.

In the running of well instruments, such as survey instruments which measure the inclination of a well bore, it is evident that the instrument should be centered within the drill pipe since the pipe naturally follows the same inclination as the well bore. The assembly, comprising the present invention, not only centers and guides the barrel A and well survey instrument contained therein but also functions as a shock absorber during the lowering and raising of the device through the well. It is pointed out that normally the drill pipe indicated at E has an elongate drill collar F connected to its lower end and below said drill collar, the drill bit (not shown) is attached. A landing plate G is usually disposed at the lower end of the drill collar F and functions to arrest or stop the survey instrument assembly in position within the collar. The bore F' of the drill collar is of a lesser diameter than the bore E' of the drill pipe.

In the use of the present apparatus, the assembly as shown in Figure 2 is connected through the adapter 27 with the usual well instrument barrel or outer casing. This disposes the flexible guide and centering member 22 immediately above the barrel or casing A. If the device is to be lowered by means of a wire line or cable 19, the line is threaded through the bore 20 of the upper element 15 and is connected to the ear or lug 21 of the body 10 and the assembly is then lowered through the drill pipe E. During such lowering, the wings or ribs 24 of the flexible guide member 22 are in a normal extended position, as shown in Figure 4 and there is preferably a slight clearance between the bore E' of the drill pipe and the outer longitudinal edges of the ribs or wings; this clearance, however, is only sufficient to permit free passage of the guide member so that no substantial misalignment can occur. If the guide wings 24 strike an obstruction or restriction in the drill pipe, the particular disposition of said wings with respect to a radial plane from the center of the mandrel 11 allows said wings to be moved or folded inwardly into an overlapping relation with respect to the body 23 so that in effect the outer diameter of the guide member is reduced to permit free passage thereof through the restriction. It is noted that because of the particular disposition of the wings toward substantially a tangential position with regard to the body portion 23, a true radial thrust is not imparted through the wings and it is this arrangement which allows a thrust on the outer end of each wing to cause said wing to move inwardly toward a folded position overlapping the body.

The assembly is lowered until the bull plug D on the instrument barrel A strikes the landing plate G within the lower end of the drill collar. As the assembly moves into the drill collar having a smaller bore than the drill pipe, the wings or ribs 24 of the flexible guide member are folded inwardly, as shown in Figure 3. This inward movement of the guide wings reduces the effective diameter of the guide member 22 and provides for a proper centering of the member within the drill collar. Obviously, this centers the barrel A as well as the instrument contained therein within said collar so that an accurate recording can be made by said instrument. It is also apparent that during the lowering operation, the flexibility

75 of the wings 24 functions to absorb shock and jar

which may be encountered during movement of the device through the drill pipe and drill collar. Thus, these excessive shocks will not be transmitted to the instrument.

If the line 19 has been employed to lower the instrument into position, the entire assembly is removed by the same means after the instrument has been operated. However, it may not be desirable in certain cases to employ the line 19 for lowering and raising said instrument and in such cases the line is completely omitted with the assembly being made up in exactly the same manner. The entire assembly is then dropped so as to fall into the drill collar by gravity or is pumped downwardly into position. After the instrument has been actuated and the assembly is to be removed, it is only necessary to lower a suitable retrieving or fishing tool (not shown) which may be engaged beneath the undercut shoulder 18 at the upper end of the retrieving element 15. The retrieving or fishing tool may then be lifted to raise the assembly to the surface in the usual manner.

It is pointed out that the device comprises a very simple and effective arrangement for guiding and centering a well instrument barrel or casing within a drill pipe or well bore. The flexible member 22 not only functions to guide and center the assembly but also acts as a shock absorber to prevent excessive or undue shocks and jars being imparted to the well instrument during lowering and raising of the same within the well. The particular arrangement at the upper end of the assembly makes it possible to either employ a lowering line 19 for moving the assembly through the well bore or to "go-devil" the assembly without the use of said line. Whether the assembly is lowered by a wire line or is merely pumped or go-deviled to bottom makes no difference since there is no change in construction required to adapt the device to the different methods of lowering. The construction of the flexible member 22 is important since the particular disposition of the guide wings or ribs make it possible to accurately guide and center the assembly in passages of varying diameters. Because of the fact that the guide wings or ribs 24 may be folded or urged inwardly upon reaching a restricted diameter passage, the element functions to accurately guide and protect the assembly without in any manner interfering with the movement of the assembly through the well bore or drill pipe.

The flexible guide member 22 has been shown and described as mounted above the well instrument barrel but it is noted that if desired it could be attached or positioned below the barrel. As a matter of fact, in some instances it might be desirable to provide two of the flexible guide members, one above and one below the barrel which would definitely assure proper guiding and centering of said barrel and its instrument within the drill pipe or well bore.

The foregoing description of the invention is explanatory thereof and various changes in the size, shape and materials, as well as in the details of the illustrated construction may be made, within the scope of the appended claims, without departing from the spirit of the invention.

We claim:

1. A guide device and retrieving structure 70

adapted to be connected to the outer casing of a well instrument as a unit and including, a support having a cylindrical portion which is axially aligned with the casing when connected thereto, a flexible guide member mounted on said support, said member comprising a tubular body portion received on the cylindrical portion of the support and having elongate guide elements in the form of ribs projecting outwardly therefrom at spaced points therearound, said ribs being disposed longitudinally of the body and lying normally in planes which pass to one side of the axis of the tubular body but capable of being flexed to a position outside of the normal plane, a retrieving head detachably connected to the upper end of the support and having means engageable by a retrieving tool, whereby the assembly may be lifted by means of said tool, and means for connecting a lowering and retrieving line directly to the support when desired and including an axial passage through the retrieving head.

2. A guide device adapted to be connected to the outer casing of a well instrument and including, a cylindrical support having its lower portion reduced, a flexible guide member comprising a tubular body portion and integral longitudinally extending guide wings adapted to be mounted on said reduced portion of the support, said longitudinally extending guide wings projecting outwardly from the tubular body portion of the guide member at spaced points therearound and each being disposed in a longitudinal plane which passes to one side of the axis of the body, whereby any pressure on the outer edge portion of each guide wing will cause an inward movement of the guide wing toward a position overlapping the exterior of the body portion, an adapter coupling detachably connected to the lower end of the reduced portion and connecting the lower end of the support to the well instrument casing and also functioning to retain the guide member in position on the reduced portion of the support, a cable connecting means at the upper end of the support whereby a lowering cable may be connected therewith, and a retrieving head removably threaded onto the upper portion of the support and having an axial bore directly above the cable connecting means and through which a cable attached to the cable connecting means may extend, said retrieving head acting as a protector for the cable connecting means and making it possible to retrieve the device in the event a lowering cable is not employed.
